UNITED STATES PATENT OFFICE.

HARRY S. WILLIAMS, OF SPRINGFIELD, OHIO, ASSIGNOR TO THE RIDGELY TRIMMER COMPANY, OF SPRINGFIELD, OHIO, A CORPORATION OF OHIO.

CUTTING-TOOL.

1,250,538.

Specification of Letters Patent. Patented Dec. 18, 1917.

Application filed March 29, 1916. Serial No. 87,554.

To all whom it may concern:

Be it known that I, HARRY S. WILLIAMS, a citizen of the United States, residing at Springfield, in the county of Clark and State 5 of Ohio, have invented certain new and useful Improvements in Cutting-Tools, of which the following is a specification.

My invention relates to improvements in cutting tools particularly adapted for trimming wall paper.

An object of the invention is to simplify and cheapen the construction of tools of this character and to make more effective the operation thereof.

A further and more particular object of the invention is to improve the construction of the cutting element proper by providing a cutting blade which may be more cheaply renewed and in which rotating parts are 20 eliminated so as to reduce wear.

In the accompanying drawings:—

Figure 1 is a side elevation of a tool embodying my improvements.

Fig. 2 is an end elevation of the same.

Fig. 3 is a top plan view.

Fig. 4 is a side elevation.

Fig. 5 is a section on the line 5—5 of Fig. 1.

Fig. 6 is a section on the line 6—6 of Fig. 3, the straight edge, however, being omitted.

Referring to the drawings, 1 represents the bottom of a carriage or gage piece, the under side of which is provided with the usual grooved projections 2 which receive 35 the overhanging metallic strip 3 of the straight edge 4, and also with the downwardly projecting lips 5 which engage the side of the straight edge; this being the usual and well known construction in tools of this 40 character. The bottom portion 1 is provided with an upwardly extending rounded block 6 which is provided with a vertically extending T-shaped guideway 7 into which leads a slotted opening 8.

Slidably connected with the carriage thus formed is a tool carrying head 9 which is in the nature of a housing within which is secured the cutting blade. In the present case this blade, which is in the nature of a flat 50 strip of steel 10 is secured to a block 11 by a screw 12 as shown in Fig. 6; a reinforcing strip 13 being preferably secured to the blade by spot welding, soldering or otherwise. The block 11 is fastened to the head in a way 55 to be readily removable. In the present case,

I have employed a screw 14 which extends through the upper portion of the head 9 into an extension 11^a of the block 11 and a screw 15 also extends through the block 11, blade 10 and its plate 13 upon the inner end of 60 which is threaded a sleeve 16 which fits snugly but removably into the hollow boss 17, thus not only assisting the screw 14 to firmly secure the block 11 to the head 9 but also more firmly clamping the blade to 65 the block. The block 11 is of a shape to fit the T-shaped groove in the part 6 so as to slidably connect it therewith, the carriage being also provided with vertically arranged beveled ribs, as indicated at 18, to inclose 70 the beveled side of the head to further assist the guiding action of the block. A spring 19 is inserted between the under side of the block 11 and the bottom of the groove 7 so as to normally force the cutting head 9 upwardly; a screw 20 secured to the block 11 and extending through the slot 8 acting as a stop.

In operation the tool is placed upon the straight edge and the operator may then by 80 hooking his forefinger under the boss 17 and pressing down upon the head 9 at the thumb place 9^a, force the blade 10 in contact with the paper to be cut and slide the tool along the straight edge. Heretofore in tools of this 85 character the cutting element has been in the nature of a disk rotatably mounted on the head 9. As the bearings for the disk wear, the disk will wobble, occasioning frequent renewal. By my improved construction, the 90 employing of the non-rotating cutting blade not only eliminates this trouble, but also, when it becomes necessary to renew the cutting blade from wear on the cutting edge thereof, this can be done much more cheaply, 95 since the cost between the two types is quite material. By reason of the peculiar shape of the cutting edge of the blade 10, which is curved upwardly in a forward direction, I am enabled to obtain in effect a draw cut 100 which is much more effective in its severing operation than the action of the rotating disk.

Having thus described my invention, I claim:—

105

1. In a cutting tool, a carriage arranged to slide along a straight edge, a head slidably connected with said carriage, a block removably secured to said head also having a slidable connection with said carriage, and 110

a removable non-rotatable cutting blade connected with said block.

2. In a cutting tool, a carriage arranged to slide along a straight edge, a head slidably connected with said carriage, a block removably secured to said head also having a slideable connection with said carriage, and a removable non-rotatable cutting blade con-

nected with said block, the cutting edge of said blade being curved upwardly in a direction of travel of said tool. 10

In testimony whereof, I have hereunto set my hand this 20th day of March, 1916.

HARRY S. WILLIAMS.
